UNITED STATES PATENT OFFICE.

MARY SPITER, OF DETROIT, MICHIGAN.

HAIR WAVER.

1,412,494.

Specification of Letters Patent. Patented Apr. 11, 1922.

Application filed August 18, 1921. Serial No. 493,408.

to all whom it may concern:

Be it known that I, MARY SPITER, a citizen of the United States, residing at Detroit, in the county of Wayne and State of Michigan, 5 have invented certain new and useful Improvements in Hair Wavers, of which the following is a specification.

This invention relates to a hair waver, and has for its object the production of a 10 simple and efficient hair waver, which may be easily operated.

Another object of the invention, is the production of a hair waver, which will wave the hair in a very short time.

15 With these and other objects in view, this invention consists of certain novel constructions, combinations, and arrangements of parts, as will be hereinafter fully described and claimed.

20 In the drawings:

Figure 1 is a side elevation of the hair waver assembled, the heating rod being shown in place.

Figure 2 is a side elevation of the device, with the heating rod removed.

Figure 3 is a side elevation of the heating rod.

Figure 4 is a section taken on line 4-4 of Figure 1.

30 By referring to the drawings, it will be seen that 1 designates a socket, which is provided with oppositely projecting folded portions 2, forming pockets 3. These pockets 3 receive the outturned ends 4 of the bow 5.

35 A sliding sleeve 6, in the form of a tube, is mounted in the socket 1, and is provided with outwardly flared ends 7, to prevent the sleeve 6 from being accidentally detached from the socket 1.

40 An elongated hair receiving tube 8, is carried by the bow 5, the bow 5 passing through an aperture 9, formed in the outer end of the tube 8. The folded portions 2 of the socket 1 are provided with notches 10, 45 through which the extremities 11 of the ends 4 extend, to facilitate the removal of the ends of the bow 5 from the socket 1. The ends of the bow 5 are bent inwardly to frictionally engage the sleeve 6 and hold the 50 sleeve in an adjusted position. The hair receiving tube 8, may be swung to the position shown in dotted lines in Figure 2, and the hair may be twisted or wound upon the same, after which, the tube 8 may be swung to the

position shown in full lines in Figure 1. 55 The sleeve 6 is then moved to the position shown in Figure 1, so that the inner end of the sleeve 6 will fit over the tube 8, and hold the tube in a set position.

A heating rod 12 is used in connection 60 with the device and is inserted in the tube 8, after the rod has been heated red hot, for the purpose of heating and curling or waving the hair twisted upon the tube 8. A handle 13 is carried by the rod 12 to facilitate the handling of the rod 12.

From the foregoing description, it will be seen that the hair may be conveniently wound upon the tube 8, and that the rod 12 may be inserted in the tube 8, in this way 70 heating the hair and waving the same, without the rod 8 coming in direct contact with the hair. By use of the device described, the hair may be conveniently waved in a very short time, and without injury to the 75 hair, such as burning.

It should be understood that certain detail changes in the mechanical construction of the device may be made without departing from the spirit of the invention, as long 80 as these changes fall within the scope of the appended claims.

The inner ends of the bow 5 are adapted to frictionally engage the sleeve 7 and hold the sleeve 7 in a set position, after the same 85 has been moved to a desired position.

Having fully described the invention, what is claimed as new is:

1. A hair waver of the class described comprising a hair supporting tube, a socket 90 associated therewith, a sleeve extending through said socket and fitting over one end of said tube, and a heating rod fitting in said tube.

2. A hair waver of the class described 95 comprising a hair supporting tube, a supporting bow constituting a pivot for one end of said tube for permitting said tube to be swung in between said bow and beyond the same, a socket associated with said tube, 100 a sleeve slidably mounted through said socket and fitting over one end of said tube for holding said tube in a set position, and a heating rod extending through said tube and sleeve.

3. A hair waver of the class described comprising a socket having oppositely extending folded portions, a bow, a tube 105

pivoted upon the outer end of said bow, the inner ends of said bow fitting in the folded portions of said socket and frictionally engaging the sides of the folded portions, a sleeve carried by said socket and slidably mounted therein, the ends of the bow frictionally engaging the sleeve for holding the same in an adjusted position, and a heating

rod extending through said sleeve and into said tube.

In testimony whereof I affix my signature in presence of two witnesses.

MARY SPITER.
